UNITED STATES PATENT OFFICE.

CLAES A. SVENSSON, OF BUFFALO, NEW YORK, ASSIGNOR OF ONE-HALF
TO WILLIAM W. OLIVER, OF SAME PLACE.

METAL-SHEARS.

SPECIFICATION forming part of Letters Patent No. 317,883, dated May 12, 1885.

Application filed April 1, 1884. (No model.)

To all whom it may concern:

Be it known that I, CLAES A. SVENSSON, a citizen of Sweden, residing in the city of Buffalo, in the county of Erie and State of New York, have invented new and useful Improvements in Metal-Shears, of which the following is a specification.

This invention relates to an improvement in that class of hand or bench shears which are used by jewelers for cutting metal, and which consists, essentially, of a stationary frame or table which carries a fixed blade, and is secured to the work-bench, and a movable arm which is pivoted to the stationary frame and provided with a movable blade.

The object of my invention is to provide means for adjusting the angle or inclination at which the movable blade meets the fixed blade, in order to produce such an adjustment of the blades with relation to each other that the metal will not curl up in cutting; and, further, to reduce as much as possible the friction between the parts, whereby the movable arm is actuated, and to provide gages for regulating the form or angle of the cut.

My invention consists, to these ends, of the improvements in the construction of the shears, which will be hereinafter fully set forth, and pointed out in the claims.

In the accompanying drawings, Figure 1 is a side elevation of my improved shears. Fig. 2 is an end elevation thereof. Fig. 3 is a vertical section in line $x x$, Fig. 1. Fig. 4 is a longitudinal section in line $y y$, Fig. 2. Fig. 5 is a cross-section in line $z z$, Fig. 1. Fig. 6 is a top plan view of the shears.

Like letters of reference refer to like parts in the several figures.

A represents the stationary frame of the machine, provided with a base-plate, a , whereby it is secured to the work-bench.

b is the stationary blade, secured in an upright position to the frame A, and b' is a horizontal table or support formed on the frame A in front of the stationary blade b .

C is an upwardly-projecting arm formed on the frame A in rear of the stationary blade b .

D is the movable arm, arranged in front of the fixed arm C, and provided at its free end with the movable blade d , which is removably

secured thereto by screws d' in a common manner.

e is the pivot on which the movable arm D swings, and which is attached to the stationary arm C. The pivot e is formed in one piece with a cylindrical bolt, E, which is seated in a cylindrical opening in the arm C, so as to turn therein. The pivot e is arranged eccentrically on the bolt E, as represented in Fig. 5, so that by turning the bolt E in its socket 55 in the arm C the pivot e is raised or lowered on the stationary arm C, thereby raising or lowering the fulcrum of the arm D and movable blade d , and decreasing or increasing the angle at which the movable blade meets the stationary blade b . In cutting metal it is desirable that the angle which the movable blade forms with the stationary blade should not be so great as to cause the metal to curl up in cutting, and this angle is readily regulated by 60 raising or lowering the pivot e on the stationary frame. The arm D is held on the pivot e by a screw-nut, e' .

The rear end of the bolt E is provided with a square or polygonal head, e^2 , so that the bolt 75 can be turned in its socket by applying a suitable wrench to the bolt. After the bolt E has been adjusted it is secured in position by a set-screw, e^3 .

f is a pin or projection formed on the bolt E, 80 on the rear side of the stationary arm C; and f', f'' are two stop-pins secured to the rear side of the arm C, to limit the turning movement of the bolt E. When the projection f rests against the stop-pin f' , as represented in Fig. 85 5, the pivot e is in its lowest position, and when the bolt E is turned, so that the projection f rests against the stop-pin f'' , the pivot e is in its highest position.

G represents the movable handle by which the 90 movable arm D is actuated. This handle is secured to a cylindrical bolt, H, which is seated in a cylindrical socket in the arm C, and provided with a pin, h , arranged eccentrically with reference to the bolt H, and projecting forwardly 95 beyond the arm C through an elongated opening, I, formed in the arm D.

i represents a roller, of steel, applied to the pin H , and fitting snugly in the elongated opening I. The latter is provided on its un- 100

derside with a bearing-piece, *j*, of steel, against which the roller *i* bears in moving the arm *D* downwardly.

Upon turning the bolt *H* by the handle *G* 5 the pin *h* moves in the arc of a circle about the axis of the bolt *H* and causes, by means of the roller *i*, an oscillating movement of the arm *D*. The roller *i* is free to turn on the pin *H*, and greatly reduces the friction between these 10 parts.

The arm *D* is held to the pin *h* by means of a screw-nut, *k*.

l is a set-screw arranged in the arm *D* above the roller *i*, for the purpose of taking up any 15 wear or play which may be created between these parts by long-continued use.

N is a gage arranged in rear of the movable blade *D*, and adjustably attached by means of a set-screw, *m*, to a horizontal bar or rod, *N'*, 20 which is secured to the rear side of the arm *D*.

The metal to be cut is placed upon the table *b'* and against the front edge of the gage *N*, whereby the width or length of the strip cut off from the rod or bar at each cut can be regulated. This width can be increased or reduced 25 by adjusting the gage *N* on the rod *N'*. The bar *N'* is provided with suitable graduations to facilitate the adjustment of the gage on the same.

o represents a gage arranged on the table *b'*, and attached thereto by a screw, *p*, which passes through a curved slot, *p'*, in said gage. The gage *o* can be adjusted at any desired angle with reference to the cutting-blades, therefore 30 by enabling the metal to be cut at any desired angle.

I claim as my invention—

1. The combination, with the stationary frame *A*, provided with a stationary blade, *b*, 40 of an arm, *D*, provided with a removable blade, *d*, and pivot *e*, made vertically adjustable on the stationary frame to regulate the angle of the movable blade with reference to the stationary blade, substantially as set forth.

2. The combination, with the stationary 45 frame *A*, provided with the fixed blade *b*, of an arm, *D*, having a movable blade, *d*, and pivot *e*, formed eccentrically on a bolt, *E*, which is capable of being turned in the stationary frame for raising and lowering the pivot *e*, substantially as set forth.

3. The combination, with the stationary frame *A* and fixed blade *b*, of the arm *D*, provided with a blade, *d*, bolt *E*, provided with an eccentric pivot, *e*, and projection *f*, and stops *f'* *f''*, secured to the stationary frame, substantially as set forth.

4. The combination, with a stationary frame, *A*, and fixed blade *b*, of the pivoted arm *D*, provided with a blade, *d*, elongated opening 60 *I*, formed in the arm *D*, actuating-pin *h*, and roller *i*, mounted on the pin *h* in the opening *I*, and hand-lever *G*, substantially as set forth.

5. The combination, with the stationary frame *A* and fixed blade *b*, of the pivoted arm 65 *D*, provided with a blade, *d*, opening *I*, formed in the arm *D*, actuating-pin *h*, roller *i*, bearing-piece *j*, and set-screw *l*, and hand-lever *G*, substantially as set forth.

6. The combination, with a stationary frame, 70 *A*, and fixed blade *b*, of a pivoted arm, *D*, provided with a blade, *d*, horizontal rod *N'*, secured to the arm *D*, and gage *N*, adjustably secured to the rod *N'*, substantially as set forth.

7. The combination, with the stationary frame *A*, provided with a fixed blade, *b*, and table *b'*, of a gage, *o*, adjustably secured on the table *b'* in front of the fixed blade *b*, and a pivoted arm, *D*, provided with a blade, *d*, substantially as set forth.

Witness my hand this 28th day of March, 1884.

CLAES A. SVENSSON.
